UNITED STATES PATENT OFFICE.

WILLIAM E. LUDLUM, OF POMPTON, NEW JERSEY.

PROCESS OF MAKING A LONGITUDINALLY-APERTURED BODY.

No. 894,023.

Specification of Letters Patent.

Patented July 21, 1908.

Application filed December 10, 1906. Serial No. 347,132.

To all whom it may concern:

Be it known that I, WILLIAM E. LUDLUM, a citizen of the United States, residing at Pompton, in the county of Passaic and State of New Jersey, have invented an Improved Process of Making a Longitudinally-Apertured Body, of which the following is a specification.

My invention relates to a process of making a longitudinally apertured body, and in carrying out the same I first provide the ingot of metal or that part thereof from which the body desired is to be rolled, with a longitudinal hole or bore, then the ingot or the aforesaid part thereof is heated to the required temperature for rolling the same; next a metal bar or rod relatively cold is inserted in the hole in the heated ingot, then the ingot and its bar or core are rolled and so reduced to the desired dimensions and then a tensile stress is applied to the said rod, sufficient to strain the same beyond its elastic limit, whereupon the said rod comes away, leaving a bore in the metal bar of substantially the same sectional area as that of the rod before the stress was applied,—as will be hereinafter more particularly described.

In the drawing, Figure 1 is a perspective view of a metallic ingot provided with a central longitudinal bore. Fig. 2 is a perspective view of a portion of an ingot provided with a central longitudinal hole in which a metallic core has been placed. Fig. 3 is a perspective view of a metal bar rolled from an ingot or a portion thereof. Fig. 4 is a view similar to Fig. 3, showing one end of the bar completely broken off and the other end of the bar severed, and Fig. 5 is a view showing the metal bar and the severed end thereof in the jaws of the device by which tension may be applied to the metallic core of the bar.

According to my present invention, I employ an ingot indicated at *a* and provided with a central longitudinal hole or bore *b* and as will be understood, the ingot *a* may be of any desired conformation and the bore *b* be of any required shape and made in the ingot by drilling, punching or any other manner known to the art. This ingot *a* or any portion thereof as indicated at *a'*, Fig. 2, is next heated to the temperature required for rolling, after which and before being rolled a rod *c* whose surface is preferably coated with a thin layer of clay or other similar material, is passed relatively cold into the opening *b* in the ingot *a* or the portion *a'* thereof, the coat-

ing of clay or other similar material being preferably employed to prevent an absolute union between the hot metal of the ingot and the colder metal rod *c*. It will be understood however that this coating may be dispensed with in certain instances and moreover that the rod *c* is made to conform approximately with the shape of the bore *b*, in the ingot *a*. The heated ingot *a* with the rod *c* inserted in the bore *b* therein, is next passed through the necessary rolls to reduce and extend the same to the desired form, which for example, is that shown in Fig. 3,—which produces the bar *d*. Now due to the difference in temperature between the ingot *a* and the bar *c*, those portions *c'* of the bar which extend beyond the ends of the ingot will not be reduced by the rolling to the same extent or proportionately to the central portion of the rod *c*, and hence between the extremities of the rod *c* and the central portion thereof and immediately within the ends of the ingot, there will be slight outwardly flaring portions *c*² in the rod *c*. One end *d'* of the bar *d* is next cut or completely broken off and thereafter the opposite end *d*² of the bar is severed or broken through. The end *d'* with that portion of the rod *c* therein is completely broken off on the dotted line 11 Fig. 3, sufficiently distant from the end of the bar to dispose of the flared portion *c'* of the rod *c* therein while the opposite end *d*² of the bar is severed completely through as indicated on the line 12, Fig. 4, which is also within the flared portion *c*² of the rod at this end of the bar. The parts hereinbefore described are then in the condition indicated in Fig. 4, whereupon the bar *d* and the end *d*² thereof are gripped in the jaws *e* of any suitable device which is adapted to have the jaws separated and so place a tensile strain on the rod *c*; such tensile strain is now applied to the rod *c* by separating the jaws *e*, and in carrying out this invention, this tensile stress must be sufficient to strain the rod *c* beyond its elastic limit, which as will be readily understood, produces a material reduction in cross section which acts progressively from the point where the rod *c* enters the cracked portion of the bar on the line 12 to the opposite end of the bar, as is indicated by the dotted line 13, Fig. 5, whereupon as will also be understood, the rod *c* comes away from the bar *d*.

It will be apparent that inasmuch as the ingot *a* and the rod *c* passing through the same, are placed together when their tem-

peratures are at the extremes and so rolled that the reduction in cross section and the consequent elongation of these parts will not be strictly proportional, and also that inasmuch as that part of the rod *c* within the severed end *d*² of the bar is of materially larger cross section than that portion of the rod *c* within the bar *d*, it will be apparent that the rod when the tensile stress is placed thereon, will always come away from the bar *d* rather than from the broken away end *d*² thereof, and for this reason it is necessary to completely break off the end *d*² of the bar and the rod therein.

15 I claim as my invention:

1. The herein described process of making a longitudinally apertured body, consisting in utilizing an ingot having a hole therein for a blank, inserting a rod in the hole in the ingot, reducing the ingot while in a heated condition to a body of the required cross section, then completely breaking off one end of the

body and rod at an appreciable distance from the end, and then withdrawing the metal rod by a tensile stress transmitted thereto.

25

2. The herein described process of making a longitudinally apertured body consisting in utilizing an ingot having a hole therein for a blank, heating said ingot, inserting a rod in the hole in the ingot, reducing the ingot while in the heated condition to a body of the required cross section, then completely severing one end of the body and rod, then completely severing the other end of the body, and then withdrawing the metal rod from the main portion of the body by a stress which is transmitted to said rod by clamping members which press against the severed end portion of the body.

Signed by me this 30th day of Nov. 1906. 40
WM. E. LUDLUM.
